UNITED STATES PATENT OFFICE.

GEORGE BERRY, OF COLNE MEAD, WEST DRAYTON, ENGLAND, ASSIGNOR TO GENERAL ELECTRIC COMPANY, A CORPORATION OF NEW YORK.

ALTERNATING-CURRENT-DISTRIBUTING SYSTEM.

1,101,051.

Specification of Letters Patent. Patented June 23, 1914.

Application filed October 17, 1908. Serial No. 458,194.

To all whom it may concern:

Be it known that I, GEORGE BERRY, of Colne Mead, West Drayton, in the county of Middlesex, England, have invented certain new and useful Improvements in Alternating-Current-Distributing Systems, of which the following is a full, clear, and exact description.

My invention relates to alternating current systems of distribution wherein main and supplemental transformers are employed in a manner somewhat resembling that described in the United States Patent No. 800,538 to A. F. Berry.

The object of my invention is to modify and improve the arrangement described in that patent whereby important practical advantages in the construction and operation of the apparatus employed are obtained, including a reduction in the total capacity of the apparatus over that heretofore required and a reduction of the operating losses. To accomplish this object in a single phase system I preferably employ a plurality of main transformers and a supplementary transformer. The primary winding of a main transformer is connected in series with the primary winding of the supplementary transformer, and these series connected windings together are connected in parallel with the primary winding of another main transformer across the primary supply conductors. The secondary windings of the corresponding transformer are similarly connected across the secondary conductors of the distributing system. As the load varies through a predetermined value the supplementary transformer is inserted into and removed from the circuit by a relay which may be quite similar in structure and connections to that shown in the above mentioned U. S. Letters Patent. The switch mechanism and relay and the various transformers, as will be obvious, may be located respectively in any suitable place, each without respect to the other apparatus.

For a better understanding of my invention reference may be had to the accompanying drawing which illustrates diagrammatically a set of connections for a single phase system involving my invention, for, although my invention is not limited in its applicability to single phase systems, this application is one of the simplest.

Two main transformers A—B, and a sup-

plementary transformer C are employed. The primary winding *c* of the supplementary transformer C, is connected in series with the primary winding *a* of the main transformer A, and these windings are collectively connected in parallel with the primary winding *b* of the main transformer B, across the primary supply conductors *d e*. The corresponding secondary windings *a'*, *c'* and *b'*, of the transformers are similarly connected in series-parallel across the secondary supply conductors *f g*.

h is the relay winding connected in series with the primary conductor *d* between the transformers and the source of energy and is adapted to effect through the double acting electro-magnetic device *n*, simultaneous operation of the movable switch contacts *i j* pertaining to the stationary contacts *k m*, and short-circuit the primary and secondary windings *c*, *c'* of the supplementary transformer C, or open the shunt about these windings to insert them into their respective circuits. This is accomplished in the manner described in the specification of the U. S. Patent No. 800,538, referred to above. As long as the load is sufficiently low to warrant the use of the supplementary transformer C, the parts will remain in the position shown, whereas when the load rises to a point at which it is necessary to cut the supplementary transformer out of circuit, the relay *h* will act through the electro-magnetic device *n* to close the switches constituted by the elements *i j* and contacts *k m*. Then the circuit is completed between the primary conductors through the winding *b* of the transformer B and in parallel to it from the line *e* through the winding *a* of transformer A, and through the shunt about the winding *c* and the contacts *k* and *i* to the conductor *d*; likewise the secondary circuit is then completed through winding *b'* and in parallel to it through the winding *a'* and the shunt about the winding *c'* including the contacts *m* and *j*.

By the means described, the relay *h* employed for controlling the operation of the switch mechanism through the electro-magnetic device *n* can be made smaller than heretofore; *i. e.*, with fewer turns and therefore of less inductance and resistance than usual because it acts with comparatively big loads in each direction. The supplementary transformer can be made quite

small, say of about one kilowatt capacity for use with main transformers of large capacity, for example, of about one hundred kilowatts, as the relay is in no way dependent upon it for operation, and the total capacity of the main transformer need be but sufficient to carry the maximum load. One relay only will be necessary for the several main and supplementary transformers, and the operating voltage will be maintained approximately constant in the substation.

While the above arrangement has been described for use in connection with two main transformers and a single supplementary transformer it will be obvious that any suitable number of main and supplementary transformers may be used and the arrangement modified to meet the requirements of various distributing systems all falling within the scope of my invention.

What I claim is:

1. In an alternating current distributing system, a plurality of main transformers, a supplementary transformer, one main transformer having its primary winding connected in parallel with the series connection of the primary winding of a second main transformer and the primary winding of the supplementary transformer across the primary supply conductors, the secondary windings of said transformers being similarly connected across the secondary conductors of the distributing system, and a switch mechanism whereby the supplementary transformer may be placed in circuit or removed from the circuit independently of the connections to the main transformers substantially as described.

2. In an alternating current distributing system, a plurality of main transformers, a supplementary transformer, one main transformer having its primary winding connected in parallel with the series connection of the primary winding of a second main transformer and the primary winding of the supplementary transformer across the primary supply conductors, the secondary windings of said transformers being similarly connected across the secondary conductors of the distributing system, and a switch mechanism comprising a relay and means controlled thereby for removing the supplementary transformer from the circuit or placing it in circuit as the load on the system rises above or falls below a predetermined amount substantially as described.

3. In an alternating current distributing system, a plurality of main transformers, a supplementary transformer, one main transformer having its primary winding connected in parallel with the series connection of

the primary winding of a second main transformer and the primary winding of the supplementary transformer across the primary supply conductors, the secondary windings of said transformers being similarly connected across the secondary conductors of the distributing system, and a switch mechanism comprising a relay actuated by the rise and fall of the load upon the system and means controlled thereby for automatically removing the supplementary transformer from the circuit or placing it in circuit, substantially as described.

75

4. In an alternating current distributing system in combination, a plurality of main transformers, a supplementary transformer, a main transformer having its primary winding connected in parallel with the series connection of the primary winding of a second main transformer and the primary winding of the supplementary transformer across the primary supply conductors, the secondary windings of said transformers being similarly connected across the secondary supply conductors of the distributing system, a relay arranged in series with one of the supply conductors in such a manner that the relay is controlled by current passing to or from all the transformers and means controlled thereby whereby the system can be altered from a condition in which the energy is being converted by all the main transformers in parallel with the supplementary transformer in series with one of the main transformers to a condition in which all the main transformers are connected in parallel without the supplementary transformer and vice versa substantially as described.

5. In an alternating current distributing system, a plurality of main transformers, a supplementary transformer, one main transformer having its primary winding connected in parallel with the series connection of the primary winding of a second main transformer and the primary winding of the supplementary transformer across the primary supply conductors, the secondary windings of said transformers being similarly connected across the secondary supply conductors of the system, a relay arranged in series with a supply conductor and means controlled thereby for automatically cutting the supplementary transformer out of circuit substantially as described.
